UNITED STATES PATENT OFFICE

2,384,000

AXIAL FLOW FAN AND COMPRESSOR

Frank L. Wattendorf, Dayton, Ohio

Application May 4, 1944, Serial No. 534,123

10 Claims. (Cl. 230—122)

(Granted under the act of March 3, 1883, as
amended April 30, 1928; 370 O. G. 757)

The invention described herein may be manufactured and used by or for the Government for governmental purposes, without the payment to me of any royalty thereon.

This invention relates to improvements in axial flow fans, pumps, compressors, and the like of the curved lattice type, i. e., in which the pressure coefficient is in the neighborhood of .5 or greater and the blade chord to spacing ratio approaches or is greater than one.

In the design of axial flow fans to suit definite operating conditions it has heretofore been the practice to employ the single airfoil theory as in propeller design. In the application of the single airfoil theory, empirically corrected values of the lift coefficient C_l , and drag coefficient C_d , of the airfoil section employed are used to determine the pitch distribution to give a desired delivery against a known pressure head at a fixed design speed. By several trial computations the proper blade angle settings at a selected number of stations on the blade radius can be determined and, permitting the thrust for one blade and the total thrust to be computed, the air delivery for a multiblade fan can be readily determined. When the design requirements are such that in order to obtain a given delivery against a higher static pressure with a fixed fan diameter and operating speed, it is necessary to increase the blade area and finally increase the number of blades so that the spacing ratio or ratio of blade chord to mean blade spacing approaches one. When the blade chord to blade spacing ratio reaches approximately six-tenths or seven-tenths, the interference effects between the blades so affect the values of lift and drag coefficients that the conventional single airfoil theory breaks down, due to the fact that no criteria exist at present for determining the corrections to lift the drag coefficients for cascade airfoil arrangements. It has been customary when the above limit has been reached to go to multiple stage design which, however, entails increased loss of efficiency.

Further difficulties arise in trying to develop axial flow fans for high pressure coefficient requirements due to the fact that the spacing between blades using conventional design criteria was such that the airflow would not conform to the mean channel form between adjacent blades and burbling or air flow separation would occur, so that upon reaching a limiting pressure coefficient, there would be an abrupt drop in delivery even though additional power was supplied, the point of air flow separation being known as the pumping limit.

In my prior United States Patent No. 2,208,215, I disclosed formulae for determining the blade angles and pitch distribution in axial flow fan blades of the curved lattice type in conjunction with fixed guide vanes; and fans constructed in accordance with the disclosure of this patent gave a much better performance in the design operating range than any commercially available equipment capable of operating in a similar pressure and volume coefficient range and at comparable speed conditions, and new values of the pumping limit were obtained.

The determination of the blade angles at entrance and exit, however, were ultimately, though not solely, determined in the patent disclosure by reference to an assumed optimum value of lift coefficient for the particular airfoil section in question.

Subsequent design and test work on axial flow fans of the character described has led to the discovery that when the ratio of blade chord to blade spacing approached or exceeded one, and for operating pressure coefficients in the neighborhood of 0.5 or greater, the line of relative flow through the blade channels or cascade arrangement was such that the deviation at outflow from a line parallel with the zero lift line of the respective blade sections became very small as the design conditions were approached and for a considerable range beyond the design point. This phenomena appeared to be substantially independent of the blade entrance angles provided the latter were such as to give minimum shock at entrance. The construction of fans such that exit angles of the zero lift lines of the respective blade sections corresponded to the necessary design point resultant velocity vector at each radial blade station gave a very considerable increase in performance and further extended the operating range of axial flow fans beyond that attainable with the patented construction. A very marked improvement has also resulted in delaying flow separation, and separation, if it occurs, is very gradual, with no abrupt drop in delivery, so that the pumping limit is extended to still lower delivery values.

The principal object of the invention is to provide means for constructing axial flow fans capable of giving a high pressure boost per stage and to obtain a very low pumping limit.

It is a further object of the invention to provide means whereby the blade angles and pitch distribution of a curved lattice axial flow fan stage can be determined when the fan stage includes as a part thereof, fixed guide vanes located ahead or

behind the fan stage, or both, or in combination with a contrarotating impeller or fan.

Other objects of the invention will appear by reference to the detailed description hereinafter given, and to the appended drawings in which:

Fig. 1 is a schematic view illustrating the velocity vector diagram for a single stage fan in accordance with the invention employing a series of fixed radial inlet guide of contravanes positioned ahead of the fan in the line of flow;

Fig. 2 is a view similar to Fig. 1, illustrating the use of fixed radial guide vanes behind the plane of the fan in the line of flow;

Fig. 3 is a view similar to Fig. 1, showing the velocity diagrams where fixed radial guide vanes are employed both ahead and behind the plane of the fan;

Fig. 4 is a view illustrating the velocity flow diagram where an axial flow fan stage in accordance with the invention is followed by a similar, but counterrotating stage;

Fig. 5 is a view similar to Fig. 4, showing the velocity diagrams for a contrarotating impeller arrangement employing both upstream and downstream contravanes;

Fig. 6 is a fragmentary view showing a construction similar to that outlined in Fig. 1;

Fig. 7 is a diagrammatic longitudinal sectional view illustrating a multistage axial flow blower constructed in accordance with the invention and employing fixed guide vanes between successive stages;

Fig. 8 is a view similar to Fig. 7, but illustrating the use of contrarotating fan stages; and

Fig. 9 is a view illustrating the mixed application of the features of Figs. 7 and 8 to a wind tunnel fan.

For a clear understanding of the detailed description of the invention, reference should be made to the following table of symbols and their definitions.

ΔP =total head developed by the fan or pump.

R =radius of the blade tips.

ω =angular velocity of the fan.

ρ =mass density of the fluid (air, water, oil, etc) in which the fan is operating.

A =net area of the fluid.

Q =quantity of fluid delivered per unit time.

η =total efficiency of unit for each radius.

ψ =the pressure coefficient.

ϕ =the volume coefficient.

C_L =the lift coefficient.

r =the radial distance of any blade element.

β =the mean angle of pitch.

n =the number of blades.

b =the blade chord.

a =the angle of attack of a blade element.

s =spacing ratio=

$$= \frac{bn}{2\pi r}$$

ratio of blade chord b to the spacing between two blades.

In expressing fan characteristics it is customary to employ non-dimensional coefficients to define the operating speed-pressure and volume relationships so that one fan may be compared with another if the pressure and volume coefficients are the same. The pressure coefficient ψ may be expressed by the following formula:

$$\psi = \frac{\Delta P}{\frac{1}{2} \rho (\omega R)^2}$$

or the ratio of the total pressure rise in the fan

to the dynamic pressure of air moving at the tip speed of the fan.

Similarly, the volume or delivery of the fan is expressed in terms of tip speed of the fan by means of the volume coefficient which is a non-dimensional coefficient or:

$$\phi = \frac{Q/A}{\omega R}$$

or the ratio of the mean velocity of the fluid stream through the plane of the fan to the fan tip speed.

Prior to considering the detailed aspects of the invention, a consideration will be made of the fundamental theory on which the invention is based. If we consider an axial flow multiblade fan arranged in a conduit with axial entrance of the air into the fan assumed, and the fan speed and blade angles so arranged that the discharge from the fan is axial, then there will be no pressure increase in passing through the plane of the fan, since the relative path of the air will remain unchanged. In order to create a pressure rise the relative velocity of the air passing the fan disc must be changed even though the axial component of the discharge remains constant, which means that in the fan blade channels a whirl or tangential component must be added to the air-flow, i. e., if the axial component of the flow is V both at inlet and discharge sides of the fan stage, the resultant velocity at discharge must also contain a tangential component u_F in order to develop pressure.

From aerodynamic considerations the change in the magnitude and direction of the resultant velocity of the air stream can only result because of the creation of lift by the fan blades, the axial component of the lift being the thrust which produces the acceleration of the air molecules to overcome the static head against which the fan must work. The lift over any radial section of a fan blade in turn is a result of the superimposed effects of a circulatory flow and an axial flow, the circulatory flow being of a peculiar type similar to a mathematical free vortex and the strength of the circulation Γ being a function of the lift coefficient at the particular section, the average velocity of the flow at the section and the blade chord. The circulation around the respective blade sections in turn produces the tangential component u_F of the fan discharge.

It can be shown from minimum energy considerations that for efficient operation there should be no radial component of flow in the fan discharge, which results only when the circulation about the blade sections is substantially constant, which in turn is only satisfied when the circulation is independent of radius and when the function rU_F is constant and the value of U_F at any radius r is the value of u_F at the blade tip at radius R times the ratio R/r .

In accordance with the conventional blade element theory, the value of u_F is determined for a given static pressure at the rear of the fan which must be known or assumed and from the velocity diagrams which are then determined for any radius; the blade sections as a whole are adjusted so that each section makes an angle with respect to the resultant velocity equal to the angle of attack for maximum efficiency or maximum L/D . Knowing the value of the lift coefficient for the given angle of attack, the thrust and delivery are computed and compared with the desired delivery and, if much in error, new

values of u_r must be computed or alterations made in the angle of attack of each section.

In accordance with the present invention, however, the assumption is made that the fan in conjunction with guide vanes must develop a certain ideal total head or total pressure (ΔP ideal) greater than the actual or working total pressure (ΔP) or

$$\Delta P \text{ ideal} = \frac{\Delta P}{\eta}$$

where η is the efficiency.

Now from the well-known Euler turbine law the maximum value of the ideal total head is ΔP (ideal) = $\rho(\omega R) U_f^2$ where U_f is the discharge angle at the tip is so made that the rotational component u_r so calculated is obtained and the value of u_r at any other radius is obtained by multiplying by the value of the ratio R/r at the radial station in question. The value of u_r for any radial station of a fan blade is, however, only capable of unique determination when the guide vane arrangement is known, i. e., whether prerotation guide vanes are employed or whether the fan stage proper is followed by guide vanes or a contrarotating fan stage designed to convert the kinetic energy of rotation of the flow into static pressure. The present invention therefore is concerned with a general combination of fan and guiding vane structure such that the final discharge will be axial, and generating a total head capable of overcoming the existing flow resistance. For example, upstream guiding vanes may be employed for imparting all of the necessary rotation in the flow to give the necessary total head, and the fan is employed, not only for the purpose of obtaining the necessary pressure difference, but also to convert the residual kinetic energy of rotation in the air stream into pressure. Further, the discharge angles at the respective radial stations in both guide and fan blades assemblies is accomplished by warping the blade section, as distinguished from setting the blade as a whole, and leaving the original airfoil section undisturbed, as generally practiced by the prior art.

The general application of the principles of the invention will be made clear by its application to typical cases as follows:

CASE I.—SINGLE ROTATION WITH CONTRAVANES UPSTREAM

In this case, as illustrated in the velocity flow diagrams of Fig. 1, the reference numeral 10 illustrates the development of a radial section of a series of guide vanes placed upstream of an axial flow fan or impeller having vanes 11 of airfoil section. The guide vanes 10 are designed so as to impart a rotational component to the inflowing air such that the rotational component u_r is of a magnitude sufficient to develop the desired total head ΔP . The discharge from the entrance or prerotation guide vanes enters the fan or impeller and, in passage through the fan blade channels, the kinetic energy of the rotational component of the inflow is converted into pressure by imparting a contraspin or rotation to the flow so that the delivery from the exit of the impeller is axial.

Referring to Fig. 1, the tangent to the mean camber line at the leading edge of each blade section 10 must be parallel with the axis of the inlet air or the entrance angle measured from a plane normal to the longitudinal axis of the in-

let vanes must be 90° at any radius since the guide vanes are not rotatable or: $(\beta_1)_{uc} = 90^\circ$.

The subscripts uc and dc respectively, indicate upstream and downstream contravanes.

Now from the velocity diagram of Fig. 1, it is seen that the angle of discharge $(\beta_2)_{uc}$, at any radius with respect to a plane normal to the flow and which is also the angle of the zero lift line of the guide vanes is determined by

10

$$\tan (\beta_2)_{uc} = \frac{V}{U_c}$$

where V is the axial flow velocity and U_c is the tangential component of the discharge at any radius. But in the case of non dimensional coefficients ϕ and ψ

$$\phi = \frac{Q/A}{\omega R} = \frac{V}{\omega R}$$

20 by definition so:

$$V = \phi(\omega R)$$

also the pressure coefficient

$$\psi = \frac{\Delta P}{\rho/2(\omega R)^2}$$

25 or

$$\Delta P \text{ (the total head)} = \psi \rho/2(\omega R)^2$$

and as previously noted from Euler's turbine 30 equation

$$\Delta P = \rho U_c (\omega R) \eta$$

and equating

$$\rho U_c (\omega R) \eta = \psi \rho/2(\omega R)^2$$

35 or

$$U_c = \frac{\psi(\omega R)}{2\eta}$$

and for any radius

$$U_c = \frac{\psi(\omega R)}{2\eta} \frac{R}{r}$$

substituting values of V and U_c in terms of ϕ and ψ respectively

$$\tan (\beta_2)_{uc} = \frac{\phi}{\frac{\psi}{2\eta} \frac{R}{r}}$$

50 *Runner blade angles.*—It will be apparent from the velocity diagram for the entrance to the impeller or runner that the entrance angle β_1 at any radius r must conform to the relative velocity of the discharge from the inlet vanes which is seen to be the resultant of the axial flow V and the sum of the tangential components $r\omega$ and u_c so that:

$$\tan \beta_1 = \frac{V}{r\omega + U_c}$$

60 but

and

$$U_c = \frac{\psi(\omega R)}{2\eta} \frac{R}{r}$$

65 so

$$\tan \beta_1 = \frac{\phi(\omega R)}{r\omega + \frac{\psi(\omega R)}{2\eta} \frac{R}{r}}$$

70 and dividing numerator and denominator by (ωR) gives

$$\tan \beta_1 = \frac{\phi}{\frac{r}{R} + \left(\frac{\psi}{2\eta} \frac{R}{r} \right)}$$

75

Similarly the outflow from the fan must be axial, so that the discharge portions of the blades must be bent, so that the tangential component at any radius is zero or, in other words, a contrary component U_F must be introduced into the flow through the fan neutralizing the tangential component U_c present at the fan inlet. By reference to the velocity diagram, Fig. 1, for the impeller outlet we have

$$\tan \beta_1 = \frac{V}{(U_c + r\omega) - U_F} = \frac{\phi \omega R}{U_c - U_F + r\omega}$$

But since U_F must equal U_c

$$\tan \beta_1 = \frac{\phi(\omega R)}{r\omega} = \frac{\phi}{r}$$

CASE II.—SINGLE ROTATION WITH CONTRAVANES DOWNSTREAM

This case, as illustrated in Fig. 2 and accompanying vector or flow diagrams, is seen to differ from Case I in that no prerotation guide vanes are employed, the necessary tangential component being developed in the fan and governed by the same law as for the prerotation vanes 10 of Case I, namely, that rc_u must be constant. The fan blades, Fig. 2, are indicated by reference numeral 12 and are followed by stationary guide vanes 13 designed to remove the tangential component from the discharge of the fan and deliver the air in a pure axial flow. In the downstream guide or contravanes 13 the same law is applicable as for the fan namely that (rc_u) must be constant. The inlet and exit angles in this combination are determined as follows:

Impeller blade angles

Since there is no prerotation of the inflow to the fan, the inlet angle of the blades β_1 , at any radius, can be determined from the inlet vector diagram such that

$$\tan \beta_1 = \frac{V}{\omega r}$$

and substituting for V

$$\tan \beta_1 = \frac{\phi R}{r}$$

The fan blades 12 must alter the resultant velocity vector from the inlet during the passage of air through the blade channels so as to impart a tangential component U_F determined from the total head and from the law of constant circulation, as previously described, so that from the vector diagram for the impeller discharge:

$$\tan \beta_2 = \frac{V}{(r\omega) - U_F}$$

which when substituting for V and U_F in terms of the pressure coefficient ϕ and cancelling the term (ωR) gives

$$\tan \beta_2 = \frac{\phi}{\left(\frac{r}{R} - \frac{\psi}{2\eta} \frac{R}{r}\right)}$$

Contravane angles

The contravanes must remove the residual tangential rotation from the discharge of the impeller and this results in a tangential velocity change U_{C_2} and from the vector diagram, Fig. 4, for the entrance of the after rotation vanes 13, it is seen that:

$$\tan (\beta_1) dc = \frac{V}{U_{C_2}}$$

but U_{C_2} is related to the pressure coefficient ψ such that

$$U_{C_2} = \frac{\psi(\omega R)}{2\eta} \frac{R}{r}$$

and

$$V = \phi(WR) \text{ so;}$$

10

$$\tan (\beta_1) dc = -\frac{\phi}{\frac{\psi}{2\eta} \frac{R}{r}}$$

The negative sign indicates that the guide vanes must introduce a contrary spinning effect on the airflow from that imparted in the impeller 15 which requires that the inclination of the vanes be opposite that of the impeller.

The discharge angle of the guide vanes must be such that the velocity vector V is parallel to the longitudinal axis and hence $(\beta_2) dc = 90^\circ$.

20

CASE III.—SINGLE ROTATION WITH CONTRAVANES UPSTREAM AND DOWNSTREAM

This combination, as illustrated schematically in Fig. 3, involves the use of upstream guide or contravanes 15, which are designed to impart a definite tangential component U_{C_1} to the air stream flowing into the fan, this component being some predetermined percentage K of the total rotation necessary to develop the necessary total head. The fan or impeller 16 is designed to impart unit rotation to the flow in the opposite sense so that a balance of $(i-k)$ of the required tangential component remains in the fan discharge and stationary downstream contravanes 35 17 remove the tangential component from the fan discharge and deliver the air in pure axial flow.

Upstream contravane angles

The design of the upstream contravanes is identical with that of Case I, except that the percentage factor k is introduced to express the amount of prerotation introduced by these vanes in terms of the total required amount, so that the blade angles at any radius r is determined by:

45

$$(\text{Inlet angle}) (\beta_1) wc = 90^\circ$$

50

$$(\text{Discharge angle}) \tan (\beta_2) u_c = \frac{\phi}{K \frac{\psi}{2\eta} \frac{R}{r}}$$

Fan blade angles

The entrance angles of the fan blade sections at each radius are determined in the same manner as for Case I, with the exception of the introduction of the percentage tangential rotation factor k so that the entrance angle is determined by:

55

$$(\text{Fan inlet}) \tan \beta_1 = \frac{\phi}{\left(\frac{r}{R} + K \frac{\psi}{2\eta} \frac{R}{r}\right)}$$

Similarly the discharge angles of the fan blade sections are determined in the same manner as for Case II, with the exception of the introduction of the factor $(i-k)$, which expresses the percent of tangential velocity residual in the fan discharge so that:

70

$$(\text{Fan discharge}) \tan \beta_2 = \frac{\phi}{\left(\frac{r}{R} + (K-1) \frac{\psi}{2\eta} \frac{R}{r}\right)}$$

Downstream contravane angles

The inlet angles of the downstream contravanes are determined by the same formula as for Case II above modified by the introduction of the

factor $-(1-K)$ which expresses the percentage of rotation required to be removed by the guide vanes to give axial flow and the minus sign indicating that the vane inclination is opposite from the vertical to the fan blades so that:

$$\tan(\beta_1)dc = \frac{\phi}{(K-1)\frac{\psi}{2\eta}\frac{R}{r}} \quad 10$$

The discharge ends of the downstream guide vanes must be axial so that $(\beta_2)dc = 90^\circ$.

CASE IV.—DUAL ROTATION WITHOUT GUIDE VANES

This combination, as illustrated schematically in Fig. 4, employs two fans or runners coaxially positioned and rotating in opposite directions, the upstream and downstream runners being indicated respectively by the reference characters 18 and 20. It will be seen by reference to the vector diagrams, Fig. 4, that the operating conditions for the upstream fan 18 is identical with that of the fan 12, Case II, so that the same formulae apply:

$$(\text{Entrance angles}) \tan(\beta_1)uf = \frac{R}{r} \quad 25$$

$$(\text{Discharge angles}) \tan(\beta_2)uf = \frac{\phi}{\left(\frac{r}{R} - \frac{\psi}{2\eta}\frac{R}{r}\right)} \quad 30$$

For the downstream fan impeller or runner the condition is similar to the fan 11 receiving the rotational discharge of the prerotation guide vanes 10 of Fig. 1 (Case I) and the same formulae are applicable with the exception of the negative sign which indicates that the vanes are sloped in the opposite sense than in the upstream fan. The blade section angles are then determined by:

$$(\text{Inlet angles}) \tan(\beta_1)df = -\frac{\phi}{\left(\frac{r}{R} + \frac{\psi}{2\eta}\frac{R}{r}\right)} \quad 45$$

$$(\text{Discharge angles}) \tan(\beta_2)df = -\frac{R}{r} \quad 50$$

In the formulae above relating to Case IV and as employed in Case V to be described below, the subscripts *uf* and *df* refer respectively to the upstream and downstream fans or runners.

CASE V.—DUAL ROTATION WITH CONTRAVANES

This combination, schematically illustrated in Fig. 5, employs upstream contravanes 21, oppositely rotating upstream and downstream fans or runners 22 and 23, respectively, and downstream contravanes 24. The upstream contravanes 21 are designed to impart a desired percentage *K* of the tangential rotation necessary to develop the required total head in the upstream fan, the upstream fan 22 again imparts unit rotation in the opposite direction leaving a residual spin in the upstream fan discharge of $(1-K)$. The downstream fan 23 puts in a rotation of unity in the opposite direction from that of the upstream fan 22 leaving a residual spin in the discharge of the downstream fan of $(-K)$ which must be overcome in the downstream contravanes 24 by imparting an equal and opposite spin or $+K$ thus giving an axial discharge from the downstream contravanes. The application of these governing criteria results in the following blade angle formulae:

Upstream contravane angles

$$(\text{Inlet}) (\beta_1)_{uc} = 90^\circ$$

$$(\text{Discharge}) \tan(\beta_2)_{uc} = \frac{\phi}{K\frac{\psi}{2\eta}\frac{R}{r}} \quad 60$$

Upstream runner blade angles

$$(\text{Inlet}) \tan(\beta_1)uf = \frac{\phi}{\left[\frac{r}{R} - (1-K)\frac{\psi}{2\eta}\frac{R}{r}\right]} \quad 65$$

$$(\text{Discharge}) \tan(\beta_2)uf = \frac{\phi}{\left[\frac{r}{R} + (1+K)\frac{\psi}{2\eta}\frac{R}{r}\right]} \quad 70$$

Downstream runner blade angles

$$(\text{Inlet}) \tan(\beta_1)df = -\frac{\phi}{\left[\frac{r}{R} + (1-K)\frac{\psi}{2\eta}\frac{R}{r}\right]} \quad 75$$

$$(\text{Discharge}) \tan(\beta_2)df = -\frac{\phi}{\left[\frac{r}{R} - K\frac{\psi}{2\eta}\frac{R}{r}\right]} \quad 80$$

Downstream contravane angles

$$(\text{Inlet}) \tan(\beta_1)dc = \frac{\phi}{K\frac{\psi}{2\eta}\frac{R}{r}} \quad 85$$

$$(\text{Discharge}) (\beta_2)dc = 90^\circ$$

A generalization of Case V occurs when the coefficients ψ and/or ϕ are different for the two fans. The design of the upstream contravanes and runner or fan would then be determined by the procedure of Case I, while the design of the downstream fan and contravanes would be determined as in the procedure of Case II employing appropriate values of the coefficients ψ and ϕ in each case.

A simple case occurs in the arrangement of Case V when $K=50\%$ since for this condition the blade angles for both fans are equal but opposite direction.

It should be further noted that in arrangements where upstream contravanes are employed, the spin component may be in the same sense as that added in the impeller and the downstream contravanes would then be required to take out the rotation equal to the sum of the spin components imparted in the upstream contravanes and the impeller rather than to remove the residual spin equal to the difference in tangential components imparted by the upstream contravanes and impeller, respectively.

Fig. 6, a fragmentary view, illustrates an arrangement of prerotation guide vanes and impeller similar to that described above with reference to Case I, Fig. 1, and the same reference numerals are accordingly applied. The prerotation guide vanes 10 have an overall radius *R*, the position of any radial station being indicated by radius *r*. The vanes 10 are seen to be of airfoil section having rounded leading edges for shock free entrance with a chord length *b* and the spacing between the blades at any radius *r* is indicated by *s* so that *S* the spacing ratio =

$$\frac{bn}{2\pi r}$$

where *n* = the number of blades. As seen in this figure, the inlet angle is determined as being the angle between the mean camber line *C* and a plane normal to the flow axis while the discharge angle is determined by the angle of the zero lift line as indicated with a plane normal to the flow axis. The zero lift line can be determined ap-

proximately by joining the point of the mean camber line at the fifty percent chord point by a straight line passing through the trailing edge. The required discharge angles are obtained by bending or curving the blade section so that the zero lift line makes the necessary angle with the plane normal to the axis of rotation. The same indicia and remarks with respect to blade station radius, chord, blade spacing and blade angles are equally applicable to the impeller 11 and are so applied in the drawing so that further description thereof is unnecessary.

Fig. 7 illustrates a typical application of the invention to a high pressure blower in which a blower housing 50 is provided with an inwardly flared end plate 51 which defines an annular inlet passage 52. Adjustable guide vanes 52 are positioned at the entrance of passage 52 and impart a tangential velocity to the inflowing air-stream which upon flowing into the vane free portion of the inlet passage forms a vortex which automatically causes the proper radial distribution of the tangential velocity prior to entrance into the first set of impeller vanes, this feature forming no part of the present invention being claimed in the copending application of Frank L. Wattendorf and Frank W. Williams Serial No. 520,922. A rotor hub 54 of cylindrical cross section is mounted within the housing 50 in bearings 55 and 56 provided in end plate 51 and a similar end plate 57 respectively, and the hub is adapted to be rotated by a driving shaft 58 connected to a suitable source of power not shown. The rotor hub 54 has a plurality of sets of impeller vanes 60 mounted thereon with a corresponding number of sets of stationary guide vanes 61 interposed between adjacent sets of impeller vanes to form separate blower stages. The stationary guide vanes are secured to the blower casing and the impeller and guide vane height decreases from the inlet toward the outlet passage 62 to compensate for the decrease in volume as the pressure is increased. In the design of a blower as illustrated the pressure boost per stage may be such that the pressure coefficient, volume coefficient, and blade spacing are such as to come within the confines of the present invention, and, accordingly, the guide vane and impeller vane angles may be readily determined for each separate stage of impeller followed by guide vanes by application of the principles of the invention as outlined in Case II (Fig. 2) above with the exception that any single set of guide vanes need not necessarily be designed to remove all of the spin from the flow passing therethrough and, in fact, the residual spin may be removed by controllable discharge vanes such as indicated in dotted lines at 65 which are optional.

In the blower illustrated in Fig. 8, a cylindrical casing 70 is provided with dished end plates 71 and 72 which, together with the casing, define inlet and discharge passages 73 and 74, respectively, which may be provided with controllable inlet and discharge guide vanes 75 and 76, respectively, the latter being optional and indicated in dotted lines. Hub members 77 and 78 support sets of impeller vanes 80 which at their outer periphery are secured to an annular shroud 81, to which other sets of impeller vanes 80 are suitably secured. The sets of vanes 80 are axially spaced and intermediate sets of oppositely rotating impeller vanes 82 are positioned therebetween and secured at their radially inner ends to a cylindrical rotor 85. A driving shaft 86 rotatably journaled in a bearing 87 fixed in end plate 72 is

connected to the hub member 78 and the hub member 77 is rotatably mounted on a bearing 88 in turn mounted on a driving shaft 89 journaled as at 91 in the end plate 71 and the shaft connected at its inner end to the rotor 85 to drive the same. The rotor 85 at its other end is provided with a pilot 92 journaled in a bearing 93 housed within a bore 94 in the hub 78. The driving shafts 86 and 89 are respectively driven in opposite directions by power means not shown.

The design of the blading of the blower of Fig. 7 can be handled stage by stage by the methods described with reference to Case IV (Fig. 4) above, each adjacent set of vanes 80 and 82 being considered as an individual stage.

Fig. 9 illustrates the application of the principles of the invention to a wind tunnel fan unit in which the tunnel walls form a conduit shown only in part and indicated by the reference numeral 100, the inflow being as indicated by arrow A and outflow as indicated by arrow B with guide vanes 101 and 102 positioned so as to guide the flow around the corners of the conduit. Separate driving shafts 103 and 104 are supported by bearings 105 and 106, respectively, within the tunnel and are adapted to be driven in opposite directions by external power means not shown. The driving shaft 103 has a rotor or hub 107 mounted thereon with two sets of impeller vanes 109 mounted thereon in axially spaced relation, each set of impeller vanes being preceded by a cooperating set of stationary guide vanes 110 supported by the tunnel walls to thereby form two separate blower or fan stages of the single rotation type. At a point axially spaced from the rotor 107 is a second rotor 112 which is mounted on the shaft 104 and is provided with two sets of impeller vanes 114 which cooperate with stationary guide vanes 115 supported from the tunnel walls. In this arrangement, if the discharge from the second set of impeller vanes 109 is purely axial, each fan unit may be designed by considering each as comprising two stages each including prerotation contravanes, and hence the formula of Case I (Fig. 1) would be applicable. By the use of contrarotating fan wheels it is possible to obtain a large pressure boost with fewer stages than with a single rotation unit because larger spin components can be converted to pressure in a rotating vane wheel than in stationary guide vanes and, accordingly, such an arrangement is indicated for wind tunnels or drainage pumps.

The principles of impeller or contravane design set forth above are of general application since by drawing the velocity diagram for any combination of impellers and guide vanes the vane angles and pitch distribution can be readily determined. It should be further understood that the principles of the invention are also applicable to thin sheet metal vanes since such vanes have determinable airfoil characteristics.

It will be apparent to those skilled in the art that many variations and modifications may be made falling within the scope of the invention as defined by the appended claims.

I claim:

1. In an axial flow fan or compressor stage, a vaneed axial flow impeller, a plurality of radially arranged inlet guide vanes, the design pressure coefficient for the stage being equal or in excess of .5 and the ratio of the vane chord to vane spacing in both guide vanes and impeller being one or greater than one, the guide vanes and impeller vanes having their discharge portions bent so

as to produce tangential components in the fluid flow through the fan stage having a magnitude equal, or in the case of the guide vanes, less than the amount required to give the desired total head, the discharge angles in the guide vanes and impeller being such that they impart rotation to the fluid flow respectively therethrough in opposite directions the guide vane and impeller vane cross-sections being in the form of a basic airfoil section modified by bending the discharge 10 portions of the vanes until the zero lift line of the basic section of each vane lies parallel at each radius to discharge lines making an angle with a plane normal to the axis of flow such that the product of the tangential velocity at any radius times the radius is substantially constant.

2. The structure as claimed in claim 1, in which the guide vanes constitute a second vaned impeller positioned upstream in the direction of flow from the first named impeller and rotatable in a direction opposite that of the first named impeller.

3. The structure as claimed in claim 1, in which the inlet guide vanes are fixed and in which the vanes are bent at their discharge portions such as to impart a rotation to the fluid flow therethrough less than the amount required to develop the design total head for the fan stage and a plurality of radial guide vanes positioned downstream of the impeller, the curvature of the inlet portions of the downstream guide vanes being such as to remove any residual rotation in fluid discharge from the impeller and the discharge from the last named guide vanes being axial.

4. In an axial flow compressor, a first axial flow multivaned impeller, a second multivaned impeller positioned downstream in the direction of fluid flow from the first impeller, said impellers being arranged for rotation in opposite directions respectively, and the vanes in each impeller defining fluid flow passages therethrough and the mean passage length at any radius being equal to or greater than the mean width of the passage, the impeller vanes having cross-sections in the form of a basic airfoil section modified by bending the discharge portions of the vanes so that the zero lift line of the basic section at any radius makes an angle with the plane of rotation such that a tangential component is imparted to the fluid flowing through the respective impeller capable of developing the design total head in the impeller discharge and the variation in vane discharge angle with respect to the radius being such that the product of the tangential velocity at any station times the radial distance of the station from the axis of rotation is substantially constant, and the vanes of the second impeller imparting a tangential component to the fluid received from the first impeller opposite in direction to that imparted to the fluid in the first impeller so that the discharge of the second impeller is substantially free from rotation.

5. In an axial flow compressor stage for operation at a design pressure coefficient of .5 or greater, a vane impeller, the impeller vanes having an airfoil section and defining fluid flow passages in which the ratio of mean pressure width to passage length at any radius is one or less than one, said impeller vanes having their inlet portions inclined to give shock free entrance under the design speed and flow conditions and said vanes being of an airfoil section derived from a basic airfoil section modified by bending the discharge portion of the vanes to deflect the zero

lift lines of the basic section at each radius such that the discharge flow relative to the impeller will at any radius have a rotational velocity which in terms of pressure corresponds to the design 5 total head to be developed in the compressor stage and the variation in the inlet and discharge angles with respect to the radius being such that the product of the tangential velocity of the flow times the radius of any station is constant.

6. The structure as claimed in claim 5, including stationary prerotation guide vanes located upstream in the direction of flow to the impeller and adapted to impart a rotation to the flow therethrough in the opposite sense to that imparted in the impeller and the discharge portions of the vanes being curved so that the product of the radius at any radial station on the vanes times the tangential component of velocity imparted to the fluid flow at that station by the vanes is substantially a constant.

7. The structure as claimed in claim 5, including stationary prerotation guide vanes located upstream in the direction of flow to the impeller 25 and the guide vanes being constructed and arranged to impart a rotational spin to the fluid discharged from the guide vanes with a radial velocity distribution such that the product of the tangential velocity at any radius times the 30 radius is substantially constant, and downstream guide vanes effective to remove residual spin from the impeller discharge.

8. In a curved lattice axial flow fan or compressor stage for developing pressures such that the operating pressure coefficient equals or exceeds .5, a multivaned impeller, a set of prerotation guide vanes positioned upstream of the impeller and a set of guide vanes positioned downstream of the impeller, the space between adjacent vanes forming fluid flow passages in said sets of guide vanes and impeller respectively, each passage having a mean length equal to or greater than the mean passage width, said prerotation guide vanes and said impeller vanes being of an 40 airfoil section derived from a basic airfoil section modified by bending the discharge portions of the vanes to deflect the zero lift line of the basic section at each radius so that at any radial station the direction of relative outflow, as measured by 45 the angle of the zero lift line of the vane section with a plane normal to the flow axis, shall produce a spin component in the flow capable of developing a pressure substantially equal to the design total head and a set of guide vanes positioned downstream from the impeller and effective to remove any residual spin in the discharge 50 of the impeller.

9. The structure as claimed in claim 5, in which the design tangential velocity at any radius 60 is determined by the expression

$$U_c = \frac{\psi(\omega R)}{2\eta} \frac{R}{r}$$

65 where

V_c =the tangential or spin velocity,

ψ =the design pressure coefficient for the stage,

ωR =the tip speed of the impeller, and

η =the assumed efficiency factor.

70 R is the tip radius, and

r =the radial distance of the station point in question.

10. In an axial flow fan or compressor stage 75 having a design operating pressure coefficient

equal to or greater than .5 at least two sets of fluid flow directing vanes each set comprising a plurality of vanes defining fluid flow passages therebetween the passages respectively having a mean length equal to or greater than the mean passage width and one of said sets of vanes being rotatable relative to the other set of vanes and forming an impeller the cross-sections of each of said sets of vanes being derived from a basic airfoil section modified by bending the discharge 10 portions of the vanes to deflect the zero lift line of the basic section at each radius so that the zero lift line of any vane section makes an angle with a plane normal to the axis of flow such that flow velocity parallel with the zero lift line of 15 the section produces a tangential or spin com-

ponent having a magnitude determined by the formula:

$$U_e = K \frac{\psi(\omega R)}{2\eta} \frac{R}{r}$$

where

V_c = the desired tangential or spin velocity,
 K = a constant expressed in percent and defining the amount of spin with respect to the total required to develop the design total head to be imparted in a respective set of vanes,

ψ is the design pressure coefficient,
(WR) is the tip speed of the impeller,

R is the tip radius, and

r the radius of the vane station point in question.

FRANK L. WATTENDORF.
